CONDENSER

Charles B. Tuley, Glenolden, Pa., assignor to Westinghouse Electric & Manufacturing Company, East Pittsburgh, Pa., a corporation of Pennsylvania

Application October 6, 1937, Serial No. 167,510

3 Claims. (Cl. 257—26)

My invention relates to a surface condenser, more particularly to a scoop condenser for a ship, and it has for an object to provide an improved arrangement for circulating cooling water therethrough.

A more particular object is to provide an improved arrangement for effecting forced circulation of cooling water through the condenser while maneuvering or moving astern.

It has long been known to provide condensers in ships with scoops for utilizing the velocity of approach of the sea water to effect flow through the condenser while the ship is moving ahead at sufficient speed. At other times, however, as when maneuvering or going astern, the scoop is not effective and it is necessary to provide a pump for effecting flow of water at such time. In some cases, the pump has been placed in the path of the flow effected by the scoop. This arrangement has the disadvantage that the pump imposes resistance to flow.

It is an object of my invention to provide an arrangement of the character set forth in which the pump for effecting forced circulation is not disposed in the path of water flow effected by the scoop so that it offers no resistance to such flow.

Still another object is to provide an arrangement of the character set forth in which the scoop provides flow of cooling water through the condenser in a single pass and in which the pump effects flow in two passes.

In accordance with my invention, I provide a scoop and an overboard discharge for effecting flow of water through the condenser by utilizing the velocity of approach of the sea water, while the ship is moving ahead at sufficient speed. I further provide a sea chest, of a design suitable for use while the ship is maneuvering or moving astern, and a pump for effecting forced circulation of water through the sea chest and the condenser. The pump is arranged outside the path of water flow effected by the scoop, so that it does not offer any resistance to such flow. The pump may, therefore, be designed for efficient operation instead of being designed for low resistance to flow. Also, because the pump takes its water from a separate sea chest instead of through the scoop which is designed for ahead operation, the loss in head through the scoop is avoided during astern operation. Such loss of head is considerable and imposes suction lift on the pump. In an optional arrangement, the scoop effects flow of water in a single pass through the condenser, while the pump effects two-pass flow.

These and other objects are effected by my invention as will be apparent from the following description and claims taken in connection with accompanying drawings forming a part of this application, in which:

Fig. 1 is a plan view partly in section of a scoop condenser according to one embodiment of my invention;

Fig. 2 is a side elevation thereof;

Fig. 3 is a horizontal sectional view of a second embodiment; and,

Fig. 4 is a partial horizontal section showing a modification of the valve arrangement of Fig. 3.

Referring to Figs. 1 and 2 in detail, I show a surface condenser 10 disposed in a ship whose hull is shown at 11. The condenser proper is of usual construction, having condenser tubes 12 and inlet and outlet water boxes 13 and 14 communicating with the opposite ends of the tubes. The inlet water box 13 communicates with the water outside the hull 11 through a scoop 15, a gate valve 16 and a conduit 17. The scoop 15 is of such form as to provide velocity-pressure conversion of the water flowing therethrough, the scoop utilizing the velocity of approach of the sea water relative to the ship for effecting such velocity-pressure conversion and consequent flow. The outlet water box 14 communicates with the sea water outside the hull through a conduit 18, a gate valve 19 and an overboard discharge 20. The latter may be provided with lips 21 and 22 on the forward and astern sides thereof. The construction so far described is known in the art.

In accordance with my invention, I further provide a sea chest 23 having a strainer plate 24. The sea chest 23 is connected to the inlet water box 13 by a gate valve 25 and a conduit 26. It is of a form and construction to provide suitable entrance flow of sea water at any speed and direction of movement of the ship. The conduit 26 contains a propeller pump 27 including stationary vanes 28 and moving vanes 29 mounted on a shaft 30. Any other suitable type of pump may be used. The pump is driven by a turbine 31 connected to the shaft 30, or in any other suitable manner.

The conduit 26 is connected to the inlet water box 13 adjacent the conduit 17. A flapper valve 32, hinged on a vertical pivot 33 is adapted to close either one of the conduits 17 and 27.

Figs. 1 and 2—operation

In normal operation, while the ship is moving ahead at sufficient speed, to the right as indicated by the arrow, the flapper valve 32 is posi-

tioned to close the conduit 26, as shown in dot and dash lines on Fig. 1. Sea water enters the scoop 15, which serves to convert the velocity of approach of the sea water relative to the ship into pressure. The resulting pressure is effective to cause flow of the water through the connections to the condenser, through the tubes thereof, and then to discharge the sea water through the overboard discharge 20.

When the ship is maneuvering ahead or going astern, the flapper valve 32 is moved to close the conduit 17, as shown by full lines in Fig. 1. Operation of the pump 27 is effected by energizing the turbine 31. The pump 27 then effects forced circulation of sea water inwardly through the strainer plates 24 and through the sea chest 23 and the conduit 26 to the inlet water box. The water then flows through the tubes and is discharged through the overboard discharge 20 as when the scoop 15 is effecting flow.

Inasmuch as the pump 27 is not disposed in the path of the flow of sea water effected by the scoop 15, it offers no resistance to such flow. It may, therefore, be designed for maximum projected area required for maximum efficiency for the amount of water and the head required. Furthermore, suitable flow of water into the condenser is provided by reason of the sea chest 23 which is designed so as to be suitable for such flow.

Figure 3

In Fig. 3 I show a second embodiment of my invention in which a scoop is provided to provide single pass flow through the condenser, as in the first embodiment, but in which the circulating pump is arranged to provide two pass flow. The condenser 40 comprises tubes 41, and inlet and outlet water boxes 42 and 43 communicating with the opposite ends of the tubes. The inlet water box 42 communicates with the sea water through a conduit 44 having its inlet end portion 45 formed to provide a scoop. In other words, it is of divergent form, as in Figs. 1 and 2, to effect velocity-pressure conversion. A valve 46 is provided and is adapted to shut off communication between the conduit 44 and the inlet water box 42.

The outlet water box 43 is provided with an intermediate vertical partition 47, dividing the same into two chambers 48 and 49, each chamber communicating with one-half of the tubes 41. The partition 47 is formed with an opening 50 which is adapted to be closed by a flapper valve 51. The chamber 49 communicates with an overboard discharge 52.

The chamber 48 communicates with the sea water outside the hull of the ship through an inlet conduit 53 which includes a sea chest 54. The sea chest 54 is of a form and construction to provide suitable entrance flow of sea water at any speed and direction of movement of the ship. The inlet conduit 53 is provided with a propeller pump 55 disposed therein. A valve 56 is also provided in the inlet conduit 53 for shutting off flow therethrough. Any suitable mechanism may be provided for simultaneously operating the valves 46, 51 and 56, such as the system of rotating shafts and bevelled gears indicated generally by the reference numeral 47 and including a hand wheel 58.

Fig. 3—operation

When the ship is moving ahead at sufficient speed (to the right as seen in Fig. 3) flow of sea water is effected through the condenser in a

single pass to the left as shown by the full line arrows. The valves 46 and 51 are in open position, and the valve 56 is in closed position, as shown in full lines on the drawings. The sea water enters the scoop 45, which utilizes the velocity of approach of the sea water to effect velocity-pressure conversion and consequent flow of sea water through the condenser. The sea water enters the inlet water box 42, and passes through the tubes 41 to the outlet box 43. The water entering the chamber 48 passes through the opening 50 into the chamber 49, and the water from both chambers is then discharged through the overboard discharge 52. During such flow, the propeller pump 55 is idle, and since it is not disposed in the path of the flow, it offers no resistance thereto.

When the ship is not moving ahead at sufficient speed, as when maneuvering ahead or going astern, the valves 46 and 51 are closed and the valve 56 is open as shown by the dot and dash lines. The propeller pump 55 is operated to effect flow of sea water inwardly through the sea chest to the chamber 43. Since the opening 50 is closed, the sea water flows in one pass through the tubes communicating with the chamber 48 to the chamber 42 which now serves as a reversing chamber. The water then enters the other half of the tube nest and flows in a second pass to the chamber 49, from which it is discharged through the overboard discharge 52. In this case, two-pass flow of water through the condenser is effected. With my arrangement, the pump 55 may be of maximum projected area required to provide the most efficient pump for the amount of water required and the head necessary for two-pass operation. Such a pump would offer excessive resistance to flow if disposed in the path of the flow effected by the scoop.

Figure 4

In Fig. 4, I show a modified form of the flapper valve arrangement used in Fig. 3. The flapper valve 59, hinged at 60, serves the purpose of both of the valves 51 and 56 of Fig. 3. The connection of the conduit 53 with the chamber 48a and the opening 50a in the partition 47a are so arranged that the flapper valve may close either one and leave the other open. The construction and operation of this modification is otherwise the same as that of the embodiment shown in Fig. 3.

From the foregoing description, it will be apparent that I have provided a marine surface condenser so arranged that the tubes extend in a fore-and-aft direction with respect to the ship, the tubes having their ends communicating with water boxes. The water boxes are connected to the exterior of the hull of the ship by means of first, second, and third conduits, the first conduit extending forwardly and being inclined at an acute angle with respect to the hull of the ship and the second and third conduits extending substantially at right angles to the latter. The inlet of the first conduit is formed to provide a scoop, which, when the ship is going ahead at sufficient speed, is adequate to produce flow of water through the first conduit, the tubes, and the third conduit to the overboard discharge. A pump associated with the second conduit provides for circulation of water through the latter, the tubes, and the third conduit to the overboard discharge when going astern. When going ahead above a minimum speed, valve means provide for

isolation of the second conduit and the pump from the scoop flow path including the tubes so that the scoop is effective to produce circulation. On the other hand, for conditions where the scoop would be ineffective, such as operation ahead below the minimum, maneuvering or astern, the valve means provide for isolation of the first conduit and the scoop from the pump flow path including the tubes. As shown in the drawings, it is necessary in all cases to have the first conduit communicate with the forward or inlet water box and the third conduit communicate with the aft or outlet water box and to have valve means to isolate the pump and the second conduit from the flow path of the scoop when the latter is effective and to isolate the first conduit and the scoop from the flow path of the pump when the latter is effective; however, the second conduit may communicate either with the inlet or with the outlet water box. Where the second conduit is connected to the inlet water box, the portion of the flow path provided by the tubes is identical both for the scoop and the pump so that it is merely necessary to provide valve means effective to open the first conduit and close the second and vice versa. On the other hand, where the second conduit is connected to the aft water box, as the overboard discharge or third conduit is also connected thereto, it is necessary that the valve means shall also be capable of separating the two, when the pump is effective to define the tube portion of the flow path.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. The combination of a marine condenser having ahead and astern water boxes, a condenser scoop for conveying sea water to said ahead water box, valve means for controlling flow through said scoop, a partition in said astern water box dividing the same into first and second chambers communicating with first and second groups of tubes, said partition having an opening therein, an overboard discharge communicating with said first chamber, a sea chest communicating with said second chamber, a

pump for translating sea water through said sea chest, and valve means for controlling flow through said sea chest and through the opening in said partition.

- 5 2. In condensing apparatus, the combination of a shell, a nest of tubes therein, a water box communicating with said tubes at one end, first conduit means communicating with said water box and including a scoop, first valve means for shutting off flow of water through said first conduit means, second conduit means communicating with one portion of the tubes at the second or opposite end, third conduit means having fluid translating means for effecting flow of water therethrough, and second valve means for selectively connecting a second portion of the tubes at said second end to either said second conduit means or said third conduit means, whereby, when the first valve means is open and the second valve means connects said second tube portion to said second conduit means, single pass flow of water through the condenser is effected by said scoop, and when said first valve means is closed and said second valve means connects said second tube portion to said third conduit means, two-pass flow of water through the condenser is effected by said scoop.
3. In a surface condenser, a shell, first and second water boxes connected to the ends of the shell; a partition dividing the second box into first and second chambers and having an opening providing for communication therebetween; a nest of tubes having the ends thereof communicating with the boxes and arranged so that a portion thereof communicates with said first chamber and the remainder with said second chamber; first means including a first conduit for supplying water to the first box, second means including a second conduit for supplying water to the first chamber of the second box; means providing a discharge passage for the second chamber of the second box; first, second, and third valves for opening and closing the first and second conduits and said partition opening, respectively; and means for opening and closing said valves such that, when the first means is effective to supply water to the first box, the first and third valves will be open and the second closed, and, when said second means is effective, said second valve will be open and the first and third valves will be closed.

CHARLES B. TULEY.
